TOURNIQUET

David Cohen, New York, N. Y., assignor to Safety
Tourniquet Corporation, New York, N. Y., a
corporation of New York

Application October 7, 1949, Serial No. 120,100

2 Claims. (Cl. 128—327)

1

My invention relates to physicians' and surgeons' clamp tourniquets, and comprehends improvements in the structures embodied in the patents to Harry Cohen, No. 1,957,992, dated May 8, 1934, and Reissue No. 19,924, dated April 14, 1936.

In practical experience it has been found that the eyes 6 and 7 of these patents—designed for the insertion of the fingers of the operator—are more of a hindrance than a matter of utility. They are in the way and often confuse the operator—especially the inexperienced—causing him to unintentionally jab the limb of the patient with the outer ends of the limb-embracing elements before the latter are fully extended.

These disadvantages are overcome by eliminating the eyes altogether and, instead, providing straight handle or shank portions, devoid of any jutting impedimenta, in fact, even the means for adjusting the limb-embracing elements in diverse positions, and which includes an arcuate extension is disposed remotely from the inner ends of the handles so as to permit an unobstructed and quick grasp of the handles.

Further, the ratchet teeth 13 of the arcuate plates 12, and the worm wheel 14 of Patent No. 1,957,992 are objectionable in that they confront the operator and after considerable use, the edges of the teeth and worm wheel—due to friction, become relatively sharp and jagged and tend to cut the ends of the fingers unless the operator is exceedingly careful.

In my invention, the teeth of the arcuate plate are on the outside edge, and no worm wheel is employed, thus reducing to a minimum the chances of injuring one's fingers.

Moreover, due to the manner in which the invention has been simplified, it is manifest that quantity production, at reduced cost, is assured.

To the accomplishment of the recited objects, and others, subordinate thereto, the preferred embodiment of my invention resides in the construction and arrangement of parts shown in the accompanying drawings, hereinafter described, and embraced within the scope of the appended claims.

In said drawings:

Fig. 1 is a front elevation of the tourniquet.

Fig. 2 is an edge view thereof.

Fig. 3 is an enlarged detail view, partly in section, of the adjusting mechanism, and

Fig. 4 is a top plan view of the ratchet spring.

Referring more particularly to the drawings, 5—6 designate a pair of complementary members hinged together at 7. The members com-

prise curved gripping elements 8—9 and straight handles 10—11. At a point just below the hinge 7 one handle is provided with a recess 12 terminating short of the outer wall thereof and the other handle is formed with a slot 13 which extends clear through. Recess 12 receives the rebated extension 14 of the arcuate plate 15 which is pivoted therein by cross pin 16. In this connection, it will be noted that the outer terminal 10 of the ratchet and the pivotal point 7 of members 5—6—see Fig. 3—are in substantially the same plane and located at a point considerably removed from the outer ends of the handles. A flat spring 17 is fastened to the inner edge of handle 11 by means of screw 18 and its upper free end is bifurcated at 19 so as to span extension 14 and press against shoulder 20.

Slot 13 extends clear through handle 10 and its ceiling 20 is bevelled to function as a pawl 20 for engagement with serrations 21 disposed on the inner edge of plate 15. This plate, on its outer end, carries a thumbpiece 22 which is used for disengaging the serrations 21 and pawl 20.

In practice, thumbpiece 22 is depressed against 25 the action of spring 17 to release teeth 21 from engagement with pawl 20 and permit the gripping elements 8—9 to be suitably spread apart so as to embrace the particular limb. Handles 10—11 are then constrained towards each other 30 until the desired constriction of the limb is obtained—the pawl riding over the serrations and automatically locking against reverse movement when the point of maximum constriction has been reached.

It will thus be seen that providing rectilinear handles in lieu of handles equipped with finger-eyes eliminates the likelihood of the operator becoming confused with respect to the precise function of the finger-eyes. Then, too, the fact that 35 the adjusting mechanism is located at a relatively remote point—the outer ends of the handles—gives the operator a clear sweep in the manipulation of the instrument and insures against the possibility of one's cutting the finger tips with sharp teeth and the jagged edges of a worm wheel—it being borne in mind that in the present instance the teeth face outwardly and do not require the cooperation of any ancillary adjusting device.

In its broader aspects my invention comprises not only the various means described but equivalent means for performing the recited functions. It is desired to reserve the right to effect such modifications and variations as may come fairly 55 within the scope of the appended claims.

I claim:

1. A physician's and surgeon's clamp tourniquet including complementary members hinged together, said members comprising curved limb-gripping elements and straight handle portions for operating the gripping elements, the inner terminal of one handle having a slot extending therethrough, the inner terminal of the other handle having a recess in substantial alignment with the slot, an arcuate ratchet having at one end a rebated extension and a shoulder, the extension being pivoted within the recess of one handle, a single spring fixed to the inside edge of the latter handle and having its opposite free terminal bifurcated and straddling the extension and engaging the shoulder, and the other end of the ratchet passing through the slot of the other handle and engageable with the inner wall thereof for locking the elements in a variety of positions.

2. A physician's and surgeon's clamp tourniquet including crossed complementary members hinged at their point of crossing, said members comprising curved limb gripping elements at one side of the pivot point and straight handle members at the other side of the pivot point, the handle members causing the limb encircling members to approach each other when the handles are brought together, the limb encircling members being offset with respect to each other, one of the handle members having a slot therein adjacent the pivot point with the upper part of the slot being formed into a pawl member on the outer wall of the handle member, the other handle member having a recess cut therein substantially in alignment with the slot in the other handle, an arcuate ratchet bar having upwardly

extending ratchet teeth on the portion adjacent the pivot point adapted to engage the pawl, one end of the arcuate ratchet bar having a rebated extension formed thereon which is pivotally mounted in the recess of said other handle member, and a shoulder formed by the rebated portion on the side of the ratchet bar opposite to the toothed side, a leaf spring fixed to the handle member below the recess and extending substantially parallel with the handle for a greater portion of its length and then outwardly from the handle forming a free end having a bifurcation therein, the bifurcation straddling the rebated portion of the ratchet bar and the web below the bifurcation engaging the shoulder of the ratchet bar and normally urging the ratchet bar upwardly so that the teeth of the ratchet bar are forced into engagement with the pawl when the handle members are moved to adjust the limb-encircling members, the limb-encircling members being thus locked in the adjusted position.

DAVID COHEN.
